UNITED STATES PATENT OFFICE.

EDWARD L. SCHWAB, OF CHICAGO, ILLINOIS.

CABINET.

Application filed October 20, 1922. Serial No. 595,733.

The invention relates to cabinets and has among its various objects the provision of a cabinet having one or more compartments in which articles of merchandise can be stored and having a number of cards upon which is displayed the merchandise contained in the cabinet mounted upon the outside thereof and secured in a manner to allow them to be inspected so that a selection may be made without necessitating the handling of the merchandise confined in the cabinet and subjecting it to the possibility of rendering it unsaleable.

It is an object of the invention to provide the cabinet with a rack within which the display cards are mounted, and in addition to provide the cabinet with a means for movably yet securely holding the display cards with relation to the case of the cabinet.

It is an additional object to provide the case with suitable stops which cooperate with the rack to hold the display cards in an upright position.

It is a further object to construct a rack so that it may be readily collapsed, and thereby reduce the space consumed by the cabinet during shipment or disuse.

The invention is primarily designed for displaying holiday and greeting cards and to provide a structure whereby a customer may select the desired card without necessitating handling the stock from which the selection is made which will thus insure the customer receiving a fresh piece of merchandise and also reduce losses to the merchant resulting from repeated handling of the stock by persons while making their selection.

To accomplish the above advantages the cabinet is provided with means for securing thereto suitable display cards upon which specimens of cards such as are contained in the case are mounted, the cards being attached to the cabinet so that their unauthorized removal from the cabinet will be prevented, the means, however allowing the several display cards to be moved relatively to each other so that the cards arranged in the rack may readily be inspected.

The cabinet is further provided with a

means for engaging the display cards which cooperates to maintain said display cards in an upright position.

The invention will be explained and more readily understood when read in conjunction with the accompanying drawings which illustrate various embodiments of which the invention is susceptible, it being obvious that other changes and modifications may be resorted to without departing from the spirit of the appended claims forming a part hereof.

In the drawings, Fig. 1 is a perspective view looking at the front of a cabinet constructed according to one embodiment of the invention;

Fig. 2 is a section of the uppermost portion of the cabinet particularly illustrating the rack, means for holding the display cards with relation to the rack, and the stops employed to assist in holding the display cards in an upright position;

Fig. 3 is a top plan view of the structure illustrated in Fig. 2, showing the elements in a collapsed condition;

Fig. 4 is a plan view of an element employed in the rack illustrated in Fig. 2;

Fig. 5 is an enlarged detail view of a portion of the structure illustrated in Fig. 4;

Fig. 6 is a sectional view illustrating the means for securing the element illustrated in Fig. 6 to the posts of the rack illustrated in Fig. 2;

Fig. 7 is a perspective view of a structure similar to that illustrated in Fig. 2 showing a rack which is independent of the cabinet;

Fig. 8 is a detail of a tab which is part of the display cards carried by the rack.

The structure illustrated contemplates the use of a case or cabinet 15 which is constructed to receive the plurality of drawers or compartments 16. The display card rack generally designated 17 is secured to the uppermost wall of the case or cabinet 15. This rack consists of the uprights or posts 18—18 and the annular band 19, the latter of which is supported by said posts.

A support 20 is adjustably held with relation to the band 19 of the rack by means of a set screw 21. This support is of a tubular

character as clearly shown in Figure 3 so that it will readily receive the advertisement holder generally designated 22, which consists of a frame 23 having the extension

24, the latter of which is fitted in the tubular portion of the support 20 and is adjustably held with relation to the support by means of the set screw 25.

The top of the cabinet illustrated in Figs. 1 and 2 is provided with the projections 26—26 and the element 27 which extends across the top of the cabinet and is secured to and held by said projections. The element 27 is employed to engage and hold the display cards 28 with relation to the cabinet, and is passed through the reenforced apertures 29 provided in the lower ends of the display cards 28.

This structure permits the display cards to be moved and the illustrated merchandise provided thereon readily inspected and in addition prevents the unauthorized removal of the display cards from the rack and cabinet.

The uppermost end of the cabinet 15 is further provided with a plurality of projections 30 which are provided to engage the lowermost edges of the display cards and assist to maintain said cards in an upright or proper relative position.

The posts 18 of the rack are removably fastened by means of screws to the uppermost portion 31 of the cabinet and are secured in this manner so that they may be arranged to assume the position illustrated in Fig. 3 and thereby reduce the space necessary during shipment or disuse of the cabinet.

From an inspection of Fig. 3 it will be noted that the element 22 carrying the advertisement is removed from the tubular support 20 and the latter is moved with relation to the band 19 so that it projects inwardly relatively to the outer periphery of the cabinet, which thus provides a compact arrangement which will materially reduce the space consumed by the structure during shipment or disuse.

The band 19 is composed of two parts 32 and 33, the opposite ends of which are respectively constructed to provide the projection 34 and the socket 35 open at the end and one side. This band is constructed in this manner to permit the upper end enlargement of the posts 18 to be arranged thereon and be positioned at the juncture of these portions 32 and 33 thereby permitting the extension 34 to be engaged by the set screw 36, the latter of which is threaded into an aperture provided in the enlargement of said posts. The various details shown in connection with the drawers of the cabinet do not form a part of the invention claimed in this case.

The holder for the sheets of the writing

pad 37 is designated 40 and includes an inclined extension and a spindle 41. This holder is illustrated as being part of one of the drawers 16, however, it is manifest that it need not be secured to this portion but might instead be made part of the casing of the cabinet.

Another projecting portion 42 is employed which is also inclined in a manner similar to that of element 40 but differs from this last mentioned element in that one face thereof is provided with frosted or ground glass 43 which is held with relation to the extension 42 by means of the frame 44. This last mentioned element is provided to produce a convenient structure whereby various memoranda, such as the number of cards contained in the particular drawer, or the condition thereof, etc., may be readily noted and erased after the memorandum has served its purpose.

The rack illustrated in Fig. 7 is substantially the same as that illustrated in Fig. 2 differing however in that the elements entering into the rack and other portions such as stops, etc., are mounted upon a board 48 which is independent of the cabinet.

From the foregoing description it is evident that a cabinet is provided, the structure of which will permit selections to be made without subjecting a merchant's stock to the possibility of rendering it useless or unsaleable.

It is further manifest that the customer may make his selection and make a memorandum thereof which memoranda may subsequently be handed to the clerk serving the customer. This will reduce the time necessary in making a sale and permit the customer ample time to make a selection without consuming the time of the clerk.

It is also evident that the holder for holding the memoranda so made by the customer is an advantage to the clerk.

Having thus described the invention what I claim and desire to cover by Letters Patent is:

1. In a device of the class described, the combination of a base, a frame comprised of separable sections adapted to be detachably secured together, supports for said frame, said supports being connected to said frame to allow said supports to be moved from their frame-supporting position to a position substantially parallel with the base.

2. In a device of the class described the combination of a frame and supports for said frame, said supports being apertured to receive the frame and to permit said supports to pivot with relation to said frame, said frame being separable to allow said supports to be arranged upon the frame and means for releasably locking said frame against separation.

3. In a device of the class described the

combination of a frame and supports for said frame, said supports being apertured to receive the frame and to permit said supports to pivot with relation to said frame, 5 said frame being composed of separable sections to allow said supports to be arranged upon the frame and means for releasably locking said frame against separation.

4. In a display rack the combination of a 10 base a frame and supports for holding the frame with relation to the base, said frame being composed of sections adapted to be

separably connected together, the adjacent ends of said sections being respectively provided with a projection and a socket to receive the projection, said supports having means for engaging said frame at the connection to hold said frame and supports in associated relation. 15

In witness whereof, I hereunto subscribe 20 my name this 14th day of September A. D., 1922.

EDWARD L. SCHWAB.
